UNITED STATES PATENT OFFICE

2,363,957

ENVELOPE OR CONTAINER

George H. Goff, Fitchburg, Mass., assignor to The
Brown Bag Filling Machine Company, a cor-
poration of Massachusetts

Application December 2, 1942, Serial No. 467,636

2 Claims. (Cl. 229—85)

The invention relates to envelopes or bags suitable for use in automatic measure and filling machines for the packaging of pulverulent and similar materials.

Containers of this type have become of considerable importance within recent years, because of the greatly increased use of packages of goods of various kinds put up in small quantities, and especially those adapted to be packaged by automatic packaging machinery. The general trend has been toward the development of flat bags or envelopes, and notwithstanding that numerous improvements have been made in such containers, there is still not complete satisfaction with those heretofore available, either because of excessive costs, or excessive bulkiness of the container, faultiness of functioning of the package for the size of the contents, or otherwise, sanitary considerations, and esthetic considerations, with possibly other effects not at this time enumerated.

It is therefore an aim of the present invention to effect a further step of improvement toward meeting the objections noted as well as attaining advantages in other respects. On account of the fact that gums used in securing the closures of such packets being either capable of affording a media for bacterial development or/and fungus propagation such as mold, as well as the antipathy of the public to having food come in contact with such adhesives, whether this antipathy is justified or not, it is an important aim of the present invention to embody a quick opening envelope suitable for use as a food container, and especially of pulverulent foods such as flour samples, individual cocoa servings, and other materials, in which the contents will be protected from contact with adhesive materials, not only while the package is sealed, but as it is opened and as the contents are discharged therefrom.

In prior envelopes it has been a serious objection that where the opening means consists of a bottom flap including both walls of a flat envelope folded on a crease entirely across the envelope and the flap thus formed detachably secured to the back of the envelope, when such envelope is opened by the pulling loose of the flap the creases in the paper and the inherent tendency of the paper to retain its creased or folded form cause the two walls of the envelope to tend to remain pressed together, interfering with the proper discharge of the contents and requiring the user to insert the fingers into the end of the envelope to press the walls apart, or to otherwise expend time and effort in attaining this end, with poor success in many instances. It is there-

fore an aim of the present invention to overcome this objection, while retaining the advantages of the bottom flap of the general kind indicated. One of the principal reasons for the tendency of such pull-down bottom flaps to remain closed is the attachment or continuity of both walls of the envelope in the flap portions at the side fold of the envelope, and it is an aim of the present invention to enable the complete disconnection of the extension of the front wall of the envelope from the extension of the back wall in the bottom flap of the envelope in an opening means of this general character. In detachable bottom flaps of this general type last mentioned, where the flap is secured to the back wall of the envelope by a weak adhesive, in such manner that the upturned flap may be pulled away from the back wall of the envelope and so detached therefrom, the attachment of the bottom flap to the back wall of the envelope has been lacking in security, and has involved the liability of accidental opening of the passage, and it is an aim of the present invention to increase the security of the closure while retaining all the advantages of great ease of opening and possibility of rapid manipulation for that purpose.

In such envelopes means has not heretofore been devised to enable the use of weakened lines in the paper stock to enable ready severance of the paper of the envelope along such lines as will result in a satisfactory opening of the envelope. Recent developments of methods of forming weakened lines in paper stock have made this a very certain and effective means for effecting severance of paper along arbitrary lines, with possibility of great range of direction and form in the severed parts, and it is therefore an aim of the present invention to enable the utilization of such weakened lines, especially those known as "perforations" while retaining all of the advantages of a safe sealing of the package against escape of pulverulent materials through such perforations, corresponding to the result of a glued seam across the envelope.

It is also an aim of the invention to provide such an envelope which may be opened by the simple expedient of pulling a simple tab toward the end of the envelope while the opposite end of the envelope is held, and resulting in the opening of the envelope with full clearance of the contents for discharge, without delay or further manipulation to induce the separation of the wall portions of the envelope at its opened end.

In the production of packages embodying this general style of opening means and in which a

seal is attempted by folding the end of a flattened tubular container on a transverse line so that parts of both the front and back walls are included in the flap outwardly of the line of fold and then securing this flap to the back of the package, difficulty has been experienced where thin paper is employed in the container. Very fine pulverulent material so packaged is found to sift out by escaping between the two walls at the transverse crease or fold in the central part. Where the double wall fold is not employed and a bottom flap on one wall is turned in around the bottom edge of the other wall of a continuous gum seal used so as to prevent escape of fine material at the central part of the bottom, it is found that the content still escapes at each side of the bottom of the package in the crease of the bottom flap. It is therefore an object of this invention to enable the use of my improved opening means in the last named type of fold as well as a simple flat bag closure where a bottom tongue on one wall is folded at and around the bottom edge of the other wall.

Additional objects, advantages and features of invention may be understood from the following detailed description thereof, and the accompanying drawing presenting the invention in its best known embodiment. In the drawing,

Figure 1 is a plan of the paper blank for forming a flat bag or envelope embodying my invention.

Figure 2 is a back view of the bag partly completed, showing it in its tubular form.

Figure 3 is a back view of the lower end of the bag completed, and initial manipulation for its opening being indicated in dotted lines.

Figure 3—*a* is an edge view of the bag showing a further stage in one method of manipulation for opening.

Figure 4 is a back view of the container opened.

Figure 5 is a fragmentary end view of the bag opened.

Figure 6 is a longitudinal sectional view of the lower end of a package embodying my invention, and showing the initial manipulation for opening the same.

Figure 7 is a longitudinal sectional view of the bag showing one manner of final manipulation in emptying the package.

There is illustrated an envelope formed from a blank 20 as shown in Figure 1, which includes a body portion or front wall portion 21, on which side flaps 22 and 23 are formed, adapted to be folded inward on the crease lines 24, so as to overlap and form a back wall 25 of the container, as in Figure 2. At this stage the article may be termed a flattened tube. The side flap 22 in this form of the invention is narrower than the other and is provided with a gummed zone 26 parallel to the vertical or longitudinal edge of the flap, so that when this flap is folded over the other on the line 24 the two are secured together, so that the lapped portions of the back wall are spaced from the medial longitudinal line of the envelope. From the top edge of the front wall portion 21 there is projected a longitudinal closure tongue 27, conforming to usual practices in such envelopes, and in the manufacture of this envelope this closure tongue is uncoated with gum, so as to facilitate the use of the envelope in the bag filling machine, wherein gum is usually applied to this tongue incident to the sealing of the envelope by the machine. The side crease lines of the flaps 22 and 23 indicated at 24 by dotted lines are parallel to each other, and

the upper and lower boundaries of the finished face of the front wall 21 are indicated by additional dotted lines 28 and 29, respectively, defining a rectangular boundary for the front wall 21.

5 The side flaps, and in consequence, the back wall 25, extend upwardly beyond the defined face portion of the wall 21, as indicated by the line 28, but in Figures 1 to 7, stop at the level of the line 29 defining the lower ends of the walls. From 10 the lower edge of the blank there is extended a closure tongue or bottom flap 30, coextensive with the full width of the face portion 21 of the envelope. This flap encloses a substantially triangular opener tongue area 31, and in addition, 15 integral side portions 32 shaped as lobes having arcuate bounding edges, which, as viewed in Figure 1, are inclined downwardly and curved inwardly from near the base of the flap toward the longitudinal medial line of the front wall 21 20 a distance, and are then recurved inwardly and upwardly as at 33, to points spaced apart transversely of the container and located at the sides of a wide tab element 34, usually formed with a width at its base of an inch or more, Figures 3 25 and 4 being full size of an article as produced and used. The tab has a length longitudinally of the blank from the points 33 appropriate to the uses hereinafter described, and ordinarily less than one-half inch, the example shown being 30 about one-quarter inch in depth. The base of the tab 34 preferably is inwardly of the curved boundaries of the lobes 32, and spaced from the bottom line 29 of the front wall a substantial distance, and while this is not arbitrary, it has been 35 found in practice satisfactory to space the base of the tab about an inch from the line 29 on a container 3 1/4 inches wide. The curves defining the outer edges of the lobes are, in the present instance, substantially parabolic, with the axis of 40 the parabola nearer the tab than to the side 24 of the container, although this curve may be varied as found expedient.

Adjacent the base of the bottom flap 30, the side edges of the flap are substantially aligned 45 with the lines 24, or side creases of the container and nearly or quite rectilinear, but the base portion of the flap includes fillets 35, which are small triangular areas of the blank integral with the base body of the flap and with the flaps 22 50 and 23 respectively, at and outwardly of the line 28, and outwardly of the lines 24, so that in the folding of the side flaps on the lines 24 each crease formed extends across the junction of the fillet and the flap 30 and the fillet is turned inward over the adjacent portion of the base of the flap 30, as seen in Figure 2. Then, when the flap 30 is folded on the line 28 upwardly and inwardly onto the back wall 25, as shown in Figures 3 and 6, the fillet is included within and 55 under the folded flap at each corner of the container, forming a complete closure and seal of the crease at each end and for a distance inwardly, and in addition, providing a terminal dam between the back wall 25 and flap 30 at each end of the zone or area of abutment of the flap 30 and back wall 25. The intervening lower edge of the back wall 25 lies snugly in the crease at 28.

The lobes 32 have adhesive 36 applied thereto 70 in zones spaced close to the opener tongue area 31 and extending from immediately adjacent or including the fillets to the sides of the tab 34, or close to the latter.

There is also applied to the container either on 75 the external face of the back wall 25 or the inner

face of the bottom flap 30, a narrow strip of special frangible adhesive material 37, extending rectilinearly transversely of the container parallel to and spaced slightly from the bottom edge of the back wall 25 between the fillets 35, which said edge coincides with the line 29 in the present instance. This strip of adhesive 37 is of a material which remains weaker than the structure of the paper of the container so that it may yield when the base portion of the bottom flap is drawn downward from the back wall 25, without tearing of either the flap 30 or wall 25. The strip of special adhesive material stops at the diagonal edges of the fillets, when the bottom flap is folded upward and secured, and lies with its ends within the defined area of the opening tongue 31 in the present instance, and is of a thickness approximately that of the paper of which the container is formed. Although this thickness has certain novel advantages, as will be explained, it is not essential. The gum 36 and adhering material 37 are applied by the envelope-making machine incident to the formation of the container, and the bottom flap immediately folded upward against the wall 25, by the machine, so that the flap is secured flat against the back wall. The material 37, extends between or on to the fillets 35 in the completed container, so that the partial dam formed by the fillets is completed by the material 37. In addition, the thickness of the material 37 presses the lower edge of the back wall snugly against the front wall so that sifting of fine material from within a package around the bottom edge of the back wall is prevented. In addition, the material 37 forms a continuous attachment of the back wall edge and bottom flap so that possibility of separation of the front and back wall parts on the crease of the latter due to distortion of the package form is opposed. Such separations might otherwise occur without the closely located continuous rectilinear attachment at 37, when the lower edge of a package is bent out of good rectilinear form, or under various strains to which a package of thin paper is readily subject, including, for instance, relative longitudinal movements of the front and back walls, unequal pressures in transversely spaced areas of the package, and otherwise. In this way, also, likelihood of contents coming in contact with the material 37 is minimized so that some suitable simple adhesive may be employed in the entire body of material 37, without requiring it to be of special quality, as to sterility, odor, or flavor. The momentary contact involved when the package is emptied, as will be described, will be of no material effect.

Within the flap 30, the opener tongue 31 is defined by two lines or series 38 of slits 39 formed through the paper of the blank at each side of the area 31, the series of slits being substantially rectilinear at each side, and the series extending from adjacent the respective points 33 to points close to the intersection of the side boundaries 24 of the front wall 21 and the bottom line 29 defining the lower edge of the wall 21. These slits 29 are each formed in such manner that though the paper is severed at the slit, the material of the paper at one side of each slit is not separated from material at the opposite side, but remains in contact therewith, so that the surface of the paper is not materially interrupted or roughened, and there will be a minimum liability of edge portions projecting, or of corners of objects striking the paper becoming engaged

in any of the slits so as to tend to tear the paper thereof. The slits in the present instance are so arranged that but few are required and are approximately spaced apart from each other one-eighth inch in the package of Figures 3-4, although this may be varied, or the ends stop short of lapping, in some instances.

The slits 39 are inclined generally in a direction from the lower corner or base of the bottom flap inwardly and upwardly toward the central portion of the tab 34. In the present instance, they are all located on lines arranged at an angle to the base line 29 closely approximating 30 degrees, although this angle may be somewhat varied without materially changing the function of the article. The downward inclination has a material effect in improving the opening function to be described.

In the present instance, there are but three slits in each series 38, but if shorter slits are employed more will be required. The parallel lines on which the slits are located in each series as shown are spaced approximately one-sixteenth of an inch apart, which affords good strength in resisting accidental disruption of the connection between the opening tongue 31 and the holding lobes, while disposing the short connecting ribbon 41 between the lapped ends of the slits 39 at such angle to the direction of shearing stress in the opening operation that a maximum of ease in opening and a maximum definiteness of direction of severance and separation of the tongue 31 and attaching parts is assured.

It should be noted that the tab 34 is formed with rounded outer corners at its ends, its transverse edge being rectilinear, and its sides being slightly divergent at its terminations and extending below the junction points 33 of the curved edges of the lobes therewith. Thus, the base of the tab is defined at each side by short slits 40 extending into the fabric sheet a distance. This, in addition to the angle formed by the junction of the lobe edge and tab edge, has an important function in definitely determining the point of beginning of tear and also facilitating the tear, when the package is to be opened, as will be described. At the same time the tab is held close against the back wall by the secured lobes 32 until opening of the article is deliberately practiced.

In the operation of opening the package, the package is held approximately erect in one hand, and the first and second digits of the other hand are presented with the finger nails next to the back wall 25 and longitudinally inward of the transverse end edges of the tab, and the nails engaged against this edge so as to separate it from the back wall and the same fingers pressed against its under side. The raised tab is then grasped between the same two fingers and the thumb and pulled outward from the medial plane of the container and also longitudinally outward and downward toward the bottom edge of the package where the crease line 29 is located. This causes the fabric to be torn beginning at the bottoms of the slits 40, and continuing longitudinally of the container, until the tear at each side reaches slit 39 nearest to the tab. A substantial body portion of the tongue 31 extending along these two slits is thus freed, and lifts out of the flap 30 without resistance by continued pull as described, until unsevered material at the lower end of the same two or uppermost slits 39 opposes the further lifting of the tongue. Continued longitudinal pulling of the tab then causes the shear-

ing of the outer (lower) extremities of the short ribbon-like portion 41 between the first and second slits. Before this shearing occurs, however, the ribbon-like portions permit a separation movement of the tongue 31 therebelow away from the back wall 25 a short distance, and a slight bending or twisting of the ribbon part 41 into a more or less spiral form, occurs, so that the direction of tear longitudinally is assured and possibility of a tear leading inward into the tongue 31 itself eliminated. This functioning of the material is repeated at the lower or outer ends of the successive slits until, at the one nearest the bottom of the package, the final longitudinal shear, indicated at 42 in Figure 4, reaches the bottom crease at 29a. By reason of the slight separation movement of the body of the tongue 31 from the back wall 25, the body of the tongue is bent less sharply than ribbon part 41, and shearing of the latter is consequently easier and more definite in direction. The contents of the package serve to separate the front and back walls 21 and 25 of the container, and, as will be understood, due to the inherent resiliency of the materials from which such bags are customarily formed, there is a stress set up in the walls of the bag by which the lower portions of the walls tend to separate from each other at the line 29.

As the final tearing occurs and the tongue 31 reaches the extended position shown in Figure 7, the stress in the material of the container as mentioned will cause its sides at the opening to spring apart, leaving the contents free to fall, substantially as indicated. When the bag is opened in this manner it will have the appearance and arrangement of parts shown in Figure 5.

In prior bags of this general kind, where the projection of the back wall downward beyond the line of crease remains attached at the sides to the front side portions or tongues, it tends to be moved to an angle to the mean plane of the package, thus acting as a stiffening flange which prevents free bending of that side of the opening, and opposes separation of the walls, and also after a certain amount of the contents has fallen from the package, the inherent resiliency of the material causes it to tend to close upon the remainder of the contents, so that the latter is opposed in its movement from the package; this objection being overcome by the construction and arrangement above last described in my invention.

It will be seen that by the utilization of the line of perforations or slits 38 in the relation and arrangement shown, it is made possible to use an opening tongue separable by this means without liability of the contents of the package escaping through the perforations. It will also be noted that by the use of the slits arranged as described, the weakening of the tongues 30 for the purpose of severance is ample, yet the paper is not so weakened against bending that it will be likely to crease or to bulge at the line of slits, and the tongue will lie flat against the back wall of the envelope and maintain a complete seal at the crease 29-a. In the manipulation of the package for opening after starting the tearing out of the tongue 31, it may be held in inverted position, as in Figure 3-a, with one hand grasped around the container while the tongue 31 is pulled longitudinally upward, after which the contents may be poured from the open end of the container as found most convenient.

Should the lapping of the slits 38 not be prac-

ticed, but if they are inclined as indicated, and if the upper ones in each series stop at their lower ends on lines at right angles thereto and across the upper ends of the slits next below, it will be apparent that there will be a greater amount of material in the tongue opposing the sharp bending of the sheet material at the point of shearing on each side, and consequently the bending of the paper will not be as sharp as in the ribbon-like parts 41 when opening is effected as described. But the shearing will still occur effectively ordinarily if the pull on the tab is applied longitudinally of the package, the sheer then extending longitudinally, and intersecting the next slit below near the upper end of the latter.

But if the pull on the tab should be exerted in a direction at a considerable angle to the longitudinal axis of the package toward one side edge or the other at the lines 24, there would be a tendency for the tear to extend into the body of the tongue 31 at the side opposite the lateral direction of pull on the tab, instead of leading into the next lower slit 38. A considerable variation from an exactly longitudinal pull on the tab will be accommodated by stopping the proximal ends of mutually adjacent slits on a line at right angles to the slits, but by forming the ribbon-like parts 41, all uncertainty is eliminated, and in addition, the more effective shearing is accomplished.

The use of slits in such series to form a line of separation, extending in a direction or directions having a substantial component of the direction in which shear is to occur (or, in other words, the direction of pull applied to the parts to be separated), is a material factor in preventing mis-directed shearing, and eliminates such failures. When coupled with the lapped arrangement of the mutually adjacent ends of the slits, there is still greater certainty of definite removal of the complete area defined by the series of slits. The direction and arrangement of the slits is also material in enabling the use of an exceptionally small number of slits and the wide spacing to afford ribbon yarts 41 of such substantial dimensions that likelihood of casual breakage of the package at the perforations is greatly minimized. The small number of slits as used is also a factor in assuring a neater shape to the torn-out part, as well as contributing to the rapidity and certainty of the opening operation.

The bag as described is adapted to be used in the conventional way in bag-filling machines where a large quantity of the containers are set in a bag-feeding box, in close packed relation and erect position, with the top tongues or flaps 21 extending upwardly without being creased or gummed. The machine introduces a charge into the open upper end of the container, and creases the bag at the proper line, as well as applying gum on the closing flap 27, as indicated at 43, after which the closing tongue or flap thus formed is folded and squeezed so as to effectively seal the package.

I claim:

1. A container of the character described comprising a blank of sheet material having a front wall and two side flaps lapped to form a back wall, their lower edges forming a line across the container, a bottom flap extended integrally from the lower edge of said front wall longitudinally beyond said back wall and folded up-

wardly at the said lower edges of the back wall, fillets integral with the side and bottom flaps formed at each side of the junction of said bottom flap and said front wall and extended laterally from the lines of fold of the side flaps and longitudinally beyond the line of fold of the bottom flap, said bottom flap having respective series of perforations at each side defining a substantially triangular central tongue having a broad base coincident with the base of the flap and a narrow portion at the extremity of the flap, said flap including integral lateral parts outwardly of and adjacent the narrower part of said tongue, an adhesive in permanent securing engagement between said lateral parts and the

underlying wall of the container, said tongue throughout its area being free of said wall, and a dam between the flap and underlying wall across the bottom of the container below said 5 perforations, said dam consisting of a strip of material coengaged between the base of said tongue and the said back wall closely adjacent the lower edge of the latter but within the longitudinal extent of and abutting said fillets and being of a material structurally weaker than the sheet material of said blank.

2. The structure of claim 1 in which said strip of material between the fillets is of a thickness substantially the same as that of the fillets.

GEORGE H. GOFF.
